OSCAR BERNIER, OF FALL RIVER, MASSACHUSETTS, ASSIGNOR TO DRAPER COMPANY,
OF HOPEDALE, MASSACHUSETTS, A CORPORATION OF MAINE.

FILLING-REPLENISHING LOOM.

1,107,400.

Specification of Letters Patent. Patented Aug. 18, 1914.

Application filed September 23, 1913. Serial No. 791,428.

To all whom it may concern:

Be it known that I, OSCAR BERNIER, a citizen of the United States, and residing at Fall River, county of Bristol, State of Massachusetts, have invented an Improvement in Filling-Replenishing Looms, of which the following description, in connection with the accompanying drawing, is a specification, like characters on the drawing representing like parts.

This invention relates to improvements in filling detecting mechanism for looms whereby the absence of filling is detected and a change in the operation of the loom automatically caused to replenish the exhausted shuttle or to substitute a full bobbin for an empty one.

This invention, while not restricted to such use, is particularly adapted for double detector looms of the Northrop type, wherein two filling detectors are employed to detect filling failure on alternate picks, one of said detectors directly controlling the operation of mechanism for changing the operation of the loom, the other, or auxiliary detector upon detection of failure of filling causing such mechanism to be operated by or through the first named detector. In looms of this character the main detector has been operated from the auxiliary detector by the outward movement of the auxiliary fork slide imparting a partial rotation to the rock shaft which controls the filling replenishing mechanism thereby retracting the main filling fork so that the same will not touch the filling when the weft-hammers are carried to their forward position. The filling fork therefore will not be tilted and upon the retraction of the weft-hammers the tail of the fork will engage the hook and thereby cause the main fork slide to complete the rotation of the controlling rock shaft for the replenishing mechanism and effect the substitution of a new bobbin in the shuttle.

One of the principal objects of my invention is to provide an attachment which can be applied to a filling fork detector loom without material modification thereof and which will positively insure the operation of the main filling fork upon detection of absence of filling by the auxiliary filling fork.

Another object of the invention is to provide means for positively locking the main filling fork in engagement with its hook

upon detection of absence of filling by the auxiliary filling fork and maintaining it in locked condition until the replenishing action has been completed.

Another object of the invention is to provide means positively actuated by the controller for the replenishing mechanism to disengage the auxiliary filling fork from its hook after the replenishing operation has been effected.

Other objects of the invention will more fully appear from the description and drawings and will be pointed out in the following claims.

In the drawings: Figure 1 is a top plan view centrally broken out of a sufficient portion of a double detector loom to illustrate my invention and its application to an automatic filling replenishing loom. Fig. 2 is an end elevation partly in section of my invention as applied to a loom, showing the relative positions of the filling fork and the lay, and also including in dotted lines an illustration of the position of the rod for disengaging the auxiliary fork tail from its hook, upon the completion of the replenishing operation. Fig. 3 is a detail view of the auxiliary filling fork, its hook, and the wire for disengaging the fork tail from the hook.

Referring to Fig. 1 the partly illustrated hopper 1 at the right is of the well known Northrop construction having a transerrer 2 operated through a replenishing controller rock shaft 3 which is rocked by the main filling fork mechanism preferably located at the shipping side of the loom. These parts may be of the ordinary construction used in automatic filling replenishing looms.

As illustrated in the drawing the main detector is provided with a filling fork 4 mounted upon a slide 5 guided in suitable ways in the frame of the machine. The vibrator 6 is provided with the usual hook 7 adapted to engage the tail of the filling fork 4 upon absence of filling in the usual manner common to this type of loom. The operation of the main filling fork is therefore that of the ordinary fork used in the Northrop loom to wit: When the fork 4 is engaged by the filling upon the forward movement of the lay it is tilted and the tail lifted, so that when the hook carried by the vibrator 6 begins its outward stroke the hook 7 passes beneath the tail of the fork without engage-

ment therewith. If, however, there is an absence of filling the filling fork 4 will not be tilted and upon the outward movement of the vibrator its tail will engage the hook 7 of the vibrator 6; the slide 5 will be forced outward until its end engages an arm 8 upon the rock shaft 3, thereby causing the operation of the filling replenishing mechanism.

The auxiliary fork 10 used in connection with this invention may be likewise mounted upon a slide 11 of the ordinary construction and adapted to coöperate with a vibrator 12 carrying a hook 13 of the usual construction, the essential features of my invention residing in the mechanism by which the operation of the auxiliary fork upon detection of absence of filling effects the depression of the tail of the main filling fork into engagement with its coöoperating hook to cause the replenishment of the shuttle. In a preferred embodiment of my invention which is illustrated herein the absence of filling causes the engagement of the tail of the auxiliary fork 10 with the hook 13, and, upon the outward movement of the vibrator, the retraction of the slide 11 so that the end thereof 14 is caused to contact with an arm 15 projecting upwardly from an auxiliary rock shaft 16 and rock the same against the tension of a helical spring 17. The rock shaft 16 is journaled in lugs 18 secured upon the frame of the machine at suitable points by bolts or other fastening devices and is connected to a clamping member which is adapted to depress and lock down the tail of the main filling fork 4 and thereby cause the main detector to actuate the filling replenishing mechanism. This clamping mechanism and its actuating devices are arranged as follows: A support 19 secured upon the breast beam is provided with an upward projection 20 terminating in the bearing 21. Pivoted upon said bearing is an inverted L-shaped member, the forward end 22 of which is adapted to engage the tail of the filling fork and hold the same in depressed position. The downwardly projecting arm 23 is pivotally attached to a link 24 which is connected with the end of an arm 25 secured to the auxiliary rock shaft 16. It will be obvious that by this connection the rocking of the auxiliary rock shaft by the outward movement of the slide 11 of the auxiliary filling fork will result in the retraction of the arm 25 against the tension of the helical spring 17, causing through the link 24 the depression of the clamping member 22 upon the fork tail. This will cause a positive locking engagement between the tail of the main filling fork 4 and the hook 7 and upon the outward movement of the slide 5 will result in the actuation of the replenishment mechanism of the loom in the manner first described. If, upon the succeeding pick or picks a filling thread is not laid the filling

fork 10 will remain in engagement with the hook 13 and the main fork again called upon to operate the replenishing mechanism until replenishment is effected.

In order to avoid the possibility that the tail of the auxiliary filling fork may become locked with its coöperating hook and thereby cause repeated actuation of the replenishing mechanism means are provided whereby the controller shaft for the replenishing mechanism disengages the tail of the auxiliary fork from its hook simultaneously with the replenishing of the shuttle. In the embodiment of this invention shown in the drawing the controlling rock shaft 3 for the replenishment mechanism is provided with a laterally extending arm 26 which engages the lower end of an upwardly extending rod 27 which terminates immediately beneath the tail of the auxiliary fork. The rod 27 is pivotally secured to the end of the arm 26 and passes freely through a guide 28 on the slide 11. It may if necessary, be offset, as at 29, to avoid contact with the lay when the latter comes forward to beat up the filling.

Upon the rotation of the controlling rock shaft to effect the replenishing of the shuttle the outer end of the arm 26 will be raised, thus forcing the rod 27 upwardly and positively raising the tail of the fork 10 from its engagement with the hook 13, thus restoring the fork to its normal detecting position. Suitable mechanism may be provided, as is customary in a loom of this character, for disengaging the takeup when absence of the filling is detected in the loom. This, however, can be of the ordinary construction and forms no part of my present invention.

This invention may be applied easily to any filling fork replenishing loom whether the same is a double feeler loom or a single feeler loom. In the former case the usual filling fork mechanism may be employed with such slight modification as is necessary to incorporate the features above described. In the latter case it is merely necessary to introduce an auxiliary standard filling fork mechanism, place a grid, such as 30, in the necessary place at the end of the lay and supply bearings for the auxiliary shaft 16 and bolt the clamping mechanism to the frame in the manner set forth above.

While this invention has been described with particular reference to its application to the replenishing of filling in automatic looms, and the replenishment of filling in the shuttles of automatic looms, it is obvious that the invention is not confined to this use, but that it may be utilized for changes in the operation of the loom, as for example, the operation of mechanism for stopping the loom upon detection of absence of filling. It is to be understood therefore, that this invention may be of general application to effect changes in the operation of looms

found desirable or necessitated by the failure of filling.

Having fully described my invention, what I claim as new and desire to secure by Letters Patent is:

5. 1. In a loom, a main filling fork adapted to effect a change in the operation of the loom upon the detection of a filling failure, an auxiliary filling fork and means operable by said auxiliary filling fork upon detection of filling failure by it to position said main filling fork in operative relation to a moving actuator so as to effect said change in the operation of the loom.
10. 2. In a loom, a main filling fork adapted to effect a change in the operation of the loom upon detection of the filling failure, an auxiliary filling fork and means operable by said auxiliary fork upon said detection of filling failure by it to depress the tail of said main filling fork into the path of the moving actuator to effect said change in the operation of the loom.
15. 3. In a loom, a main filling fork, means adapted to be operated by said main filling fork to effect a replenishment of the filling upon detection of the filling failure, an auxiliary filling fork, and means operable by said auxiliary fork upon detection of absence of filling by it to depress the tail of said main filling fork into the path of a vibrator to effect a replenishment of the filling.
20. 4. In a loom, in combination, main and auxiliary filling forks each having slides on which said forks are mounted, a vibrator and its hook for each fork, filling replenishing mechanism directly controlled as to its operation by the main fork upon detection of filling absence thereby, means operative through the detecting action of the auxiliary fork to position the tail of the main fork in the path of its hook, whereby filling replenishment will be effected.
25. 5. In a loom, in combination, main and auxiliary filling forks each having slides on which said forks are mounted, a vibrator and its hook for each fork, filling replenishing mechanism directly controlled as to its operation by the main fork upon detection of filling absence thereby, means operative through the detecting action of the auxiliary fork to position and positively lock the tail of the main filling fork in the path of its hook during the forward vibration thereof, whereby filling replenishment will be effected.
30. 6. In a loom, in combination, main and auxiliary filling forks each having slides on which said forks are mounted, a vibrator and its hook for each fork, filling replenishing mechanism directly controlled as to its operation by the main fork upon detection of filling absence thereby, means operative through the detecting action of the auxiliary fork to position and positively lock the tail of the main filling fork in the path of its hook, comprising a rock shaft adapted to be operated by retraction of the auxiliary fork slide and means actuated through said rock shaft to depress the main fork tail into the path of its hook.
35. 7. In a loom, in combination, main and auxiliary filling forks each having slides on which said forks are mounted, a vibrator and its hook for each fork, filling replenishing mechanism directly controlled as to its operation by the main fork upon detection of filling absence thereby, means operative through the detecting action of the auxiliary fork to position and positively lock the tail of the main filling fork in the path of its hook, comprising a rock shaft adapted to be operated by retraction of the auxiliary fork slide and means actuated through said rock shaft to depress and hold the main fork tail in engagement with its hook until replenishment has been effected.
40. 8. In a loom, in combination, main and auxiliary filling forks each having slides on which said forks are mounted, a vibrator and its hook for each fork, filling replenishing mechanism directly controlled as to its operation by the main fork upon detection of filling absence thereby, means operative through the detecting action of the auxiliary fork to position and positively lock the tail of the main filling fork in the path of its hook, comprising a rock shaft adapted to be operated by retraction of the auxiliary fork slide and means actuated through said rock shaft to depress and hold the main fork tail in engagement with its hook until replenishment has been effected, and means operated in conjunction with the replenishing mechanism adapted to disengage the auxiliary fork tail from its hook.
45. 9. In a loom comprising automatic replenishing mechanism, a main filling fork, a slide upon which the same is mounted, a vibrator and its hook, a rock shaft for controlling the replenishing mechanism adapted to be rocked by said slide upon detection of filling absence, an auxiliary filling fork and a slide therefor, a vibrator and its hook, an auxiliary rock shaft adapted to be rotated by the auxiliary slide upon detection of filling absence, a member operated by said auxiliary rock shaft to cause engagement of the main filling fork with its hook and thereby rotate the main rock shaft to cause filling replenishment, an arm extending laterally from said rock shaft, a rod connected to said arm, which upon restoration of the main rock shaft to normal position is adapted to disengage the tail of auxiliary filling fork from its hook.
50. 10. In combination with an automatic filling replenishing loom having main and auxiliary filling forks and vibrators adapt-

- ed to actuate the same, an attachment comprising filling fork engaging means adapted to be secured to the breast beam adjacent to the main filling fork stand, and means 5 operated by the auxiliary filling fork upon detection of failure of filling to cause said fork engaging means to position the tail of the main filling fork in the path of its vibrator to effect replenishing of the active 10 shuttle.
11. In combination with an automatic filling replenishing loom having main and auxiliary filling forks and vibrators adapted to actuate the same, an attachment comprising a lever adapted to be pivotally secured to the breast beam adjacent to the 15

main filling fork slide, an auxiliary rock shaft connected to said lever, and means carried by said shaft adapted to be engaged by the auxiliary filling fork mechanism upon detection thereby of failure of filling to cause said lever to depress the tail of the main filling fork into the path of its vibrator to effect replenishment of the active 20 shuttle. 25

In testimony whereof, I have signed my name to this specification, in the presence of two subscribing witnesses.

OSCAR BERNIER.
